UNITED STATES PATENT OFFICE

161,822

COMBINED COIN HOLDER, KEY CHAIN, MIRROR, AND CARD CASE OR THE LIKE

Herbert S. Chase, New York, N. Y.

Application July 25, 1950, Serial No. 11,397

Term of patent 14 years

(Cl. D87—3)

To all whom it may concern:

Be it known that I, Herbert S. Chase, a citizen of the United States of America, residing in New York city, county of New York, and State of New York, have invented a new, original, and ornamental Design for a Combined Coin Holder, Key Chain, Mirror, and Cardcase or the like of which the following is a specification, reference being had to the accompanying drawing, forming part thereof, wherein,

Figures 2 and 3 are side and rear elevational views, respectively, of the article, and

Figure 4 is a plan view on a reduced scale, illustrating the article in an open position.

I claim:

The ornamental design for a combined coin holder, key chain, mirror, and cardcase or the like, substantially as shown.

HERBERT S. CHASE.
